METHOD AND MEANS FOR MAKING
DIAMOND DRILL BITS

Jesse L. Havlick, Spokane, Wash.

Application May 1, 1942, Serial No. 441,407

7 Claims. (Cl. 22—122)

The present invention relates to new and useful improvements in method and means for making rotary diamond drill bits for earth boring and for making other diamond cutters and tools.

Heretofore the practice of setting diamonds as cutters in industrial tools has been a slow and tedious method done principally by hand and this, of course, is expensive as it is necessary to drill the hole the proper size and depth for the diamond, setting the diamond in the hole by hand, and then drawing the metal around the stone by means of calking which makes it impossible for the hand-setter to apply exactly the same amount of pressure to the stone on all sides, which is very important in avoiding putting extensive stresses on the stone which may cause fractures or breaks before the stone is ever used.

Also a method of setting the diamonds has been employed by casting the same in slugs, or molten metal, but because of the difference in specific gravity of the diamond, it is very difficult to hold the diamond in position while casting. This method has also presented difficulties in eliminating so-called "floating," which occurs when the diamond has raised in the molten metal before it has properly set.

Accordingly, it is an object of the present invention to overcome the difficulties above explained and to this end I have provided a method and apparatus for setting the diamonds by providing a temporary mold and inverting the mold with the diamond held in position therein onto powdered metal placed in a mold on top of the bit blank and fusing the metal and subjecting the same to predetermined pressure to produce a strong connection thereof with the bit blank and in which the diamond will be firmly embedded.

A further object is to provide a method and means of setting diamonds in drill bits and the like which are efficient and reliable in performance, relatively inexpensive to use and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the mold or diamond holder.

Figure 2 is a side elevational view thereof.

Figure 3 is a sectional view taken substantially on a line 3—3 of Figure .

Figure 4 is a vertical sectional view of the suction device for holding the diamonds in position in the mold or holder while the diamonds are temporarily secured in position in the mold.

Figure 5 is a side elevational view of a completed diamond bit constructed in accordance with my invention.

Figure 6 is a vertical sectional view thereof.

Figure 7 is an end elevational view.

Figure 8 is a vertical sectional view of the fusing mold.

Figure 9 is a sectional view taken substantially on a line 9—9 of Figure 8.

Figure 10 is a front elevational view of the combination electro-hydraulic pressure fusing or sintering machine.

Figure 11 is a side elevational view thereof.

Figure 12 is a sectional view taken substantially on a line 12—12 of Figure 10.

Referring now to the drawings in detail, the numeral 5 designates a diamond-holding mold or cup having an annular channel 6 formed therein within which the diamonds, indicated at 7 in Figure 4 of the drawings, are placed in a desired position, the bottom of the channel 6 having openings 8 therein to subject the diamonds to suction from a suction chamber 9 in which the mold 5 may be positioned and supported in its upper portion on brackets 10, the center portion of the chamber 9 being closed by a cap 11. A suction pipe 12 is attached to the chamber 9 for creating the desired suction in the chamber from a suitable source of power.

The diamonds are then sprayed with a suitable quick-drying adhesive such as collodion, shellac, lacquer or glue, this being a temporary operation to hold the diamonds in the mold while handling.

The mold, with the diamonds positioned therein, is then placed in an inverted position in a combined fusing and pressure device illustrated in detail in Figures 8 and 9 of the drawings, and comprises a bottom section 13 of conductive material including an upstanding tubular post 14 which is internally threaded for threadedly receiving the bit blank 15, the bit blank having lateral openings 16 adjacent its upper edge.

Positioned in the upper portion of the bit blank is a core 17 of non-conductive material which may be made of bone ash, plaster of Paris, or refractory brick material, and surrounding the upper portion of the bit blank and the upper portion of the tubular bit blank holder 14, is a sectional lining sleeve 18 of material similar to the core 17. A retaining collar 19 is then placed over the lining 18.

Between the core 17 and the lining 18 is placed a quantity of powdered metal 20 screened to about 200 mesh, the powdered metal being placed on top of the bit blank 15 and on top of the powdered metal is inverted the diamond holding mold 5.

The powdered metal may be a suitable alloy, depending upon the type of material the finished bit is to be used for boring.

On top of the mold 5 is placed the upper section 21 of the fusing device which has its lower end extending downwardly into the sectional lining 18 for bearing against the mold 5, the section 21 likewise being of conductive material. Connected to the section 21 is a terminal member 22 and connected to the lower section 13 is a terminal member 23, said terminals leading to a suitable source of direct current.

The fusing device is then placed in a hydraulic press designated generally at 24 and includes a base 25 having a pair of upstanding rods 26 rising therefrom on which is slidably mounted the lower pressure plate 27 on which the fusing device 13 is supported, the upper ends of the rods 26 having an upper pressure plate 28 attached thereto and which engages the top of the section 21 of the fusing device 13. The hydraulic cylinder 29 is supported on the base 25 and from the top of the cylinder projects the plunger 30 for engaging the underside of the lower pressure plate 27. A feed pipe 31 leads from the cylinder 29 to a suitable source of hydraulic pressure whereby the desired pressure may be subjected to the metal powder 20 and at the same time a heavy electric current of high amperage and density is transmitted to the upper and lower sections of the bit holder through the terminals 22 and 23 which then fuses the powdered metal and causes the diamonds to become embedded therein. The fusing action also causes the molten metal to enter the aperture 16 to firmly anchor the same to the bit.

After the bit holder and bit have been cooled, the diamond holder 5 is then removed and the bit is ready for use.

Having thus described the invention what I claim is:

1. A method of making diamond cutters comprising temporarily securing the diamonds in an open mold, inverting the mold on metal, and fusing the metal to cause embedding of the diamonds therein.

2. A method of making diamond cutters comprising placing the diamonds in an open holder and coating the diamonds with an adhesive to temporarily secure the diamonds in position in the holder, inverting the holder on a cutter stock, interposing fusible material between the diamonds and the stock, and fusing the material to

cause embedding of the diamonds therein and adherence of the material to the stock.

3. A method of making diamond cutters comprising placing the diamonds in an open holder and coating the diamonds with an adhesive to temporarily secure the diamonds in position in the holder, inverting the holder on a cutter stock, interposing fusible material between the diamonds and the stock, subjecting the diamonds and the stock to a compressing action against the material, and fusing the material to cause embedding of the diamonds therein and adherence of the material to the stock.

4. A method of making diamond cutters comprising placing the diamonds in an open holder and coating the diamonds with an adhesive to temporarily secure the diamonds in position in the holder, inverting the holder on a cutter stock, placing powdered metal between the diamonds and the stock, and fusing the metal to the diamonds and the stock.

5. A method of making diamond cutters comprising placing the diamonds in an open holder and coating the diamonds with an adhesive to temporarily secure the diamonds in position in the holder, inverting the holder on a cutter stock, placing powdered metal between the diamonds and the stock, compressing the metal between the diamonds and the stock, and fusing the metal to the diamonds and the stock.

6. Means for making cutting tools comprising an open holder adapted to contain a predetermined number of diamonds against movement in the holder in an exposed position, a fusing mold comprising upper and lower electric conductors, said lower conductor being adapted for supporting a tool stock, and for receiving powdered metal placed in the mold on the upper edge of the stock to be fused to the stock, said holder being positioned on top of the metal in an inverted position with the diamonds in contact with the metal, and means for compressing the diamonds and stock against the metal.

7. Means for making cutting tools comprising an open holder adapted to contain a predetermined number of diamonds against movement in the holder in an exposed position, a fusing mold comprising upper and lower electric conductors, said lower conductor being adapted for supporting a tool stock, and for receiving powdered metal placed in the mold on the upper edge of the stock to be fused to the stock, said holder being positioned on top of the metal in an inverted position with the diamonds in contact with the metal, and means for exerting pressure against the conductors for compressing the metal between the diamonds and stock.

JESSE L. HAVLICK.
